3 SHEETS—SHEET 3.

UNITED STATES PATENT OFFICE.

WILLIAM W. DEAN, OF ELYRIA, OHIO, ASSIGNOR TO THE DEAN ELECTRIC COMPANY, OF ELYRIA, OHIO, A CORPORATION OF OHIO.

AUTOMATIC RINGING DEVICE FOR TELEPHONE-EXCHANGE SYSTEMS.

No. 838,244.

Specification of Letters Patent.

Patented Dec. 11, 1906.

Application filed January 16, 1906. Serial No. 296,287.

To all whom it may concern:

Be it known that I, WILLIAM W. DEAN, a citizen of the United States, residing at Elyria, in the county of Lorain and State of Ohio, have invented certain new and useful Improvements in Automatic Ringing Devices for Telephone-Exchange Systems, of which the following is a specification, reference being had therein to the accompanying drawings.

My invention relates to telephone systems, and has for its object the provision of improved and simplified means whereby signaling-current may be controlled in its application to telephone-lines.

The invention is particularly intended for use in exchange systems in connection with what is known as "machine-ringing."

In all except the very smallest exchanges it is now usual to provide either a ringing-generator or some form of pole-changer wherefrom current may be derived for actuating the subscribers' bells. This current is applied to the subscribers' lines through a switch mechanism adapted to cut off its source except during the period of actual ringing, the usual form of switch employed being a manually-operated key. Such a key, however, must either be held in ringing position by an operator, ceasing its function when the operator relaxes her hold, or if it is to remain down it must be fitted with some special holding appliance or latch. A latch of this kind, which depends for its tripping upon a further act of the operator, would not be in accord with good practice, since the operator's attention might be otherwise bestowed until after the called subscriber had answered, with the annoying result of passing noisy generator-current through his receiver until the key could be finally released. Of course where supervisory signals are employed this condition would be guarded against in a degree, but not altogether; so it has been suggested to control the key or switch through a mechanism which will respond to the called-subscriber's act in taking down his receiver to thereupon immediately release the ringing-generator.

So far as I know none of the ringing systems now in use has given entire satisfaction. One reason for this lies in the necessity for ringing through the governing-relay, which is so wound as to be unresponsive to the

small volume of current permitted to pass by 55 the normal high resistance of the subscriber's line with the ringer included. It is impossible to construct this magnet so that it will be devoid of resistance and self-inductance, and hence there must always be a certain drop in efficiency of ringing where it is employed.

My present invention is in the nature of an improvement on the systems heretofore in use.

It contemplates the application of ringing-current to the wanted-subscriber's line through a suitable switch or key and the maintenance of the condition so produced until the called subscriber shall have answered his telephone, whereupon the source of ringing-current will be immediately disconnected.

It contemplates also the use of selector or so-called "harmonic" ringing-current of different frequencies, which has heretofore been impossible, for the reason that with a magnet, such as a tripping-magnet I have mentioned, in the ringing-circuit no proper adjustment of either the magnet, the circuit, or of the current itself could be had. Since the self-inductance of a circuit varies with the frequency of the current employed, it is obvious that a magnet-winding which would be suitable for a low-frequency current might and probably would seriously impede the passage of high-frequency current.

According to my present invention no electromagnet is employed, or at least no electromagnet comes at any time in the path of ringing-current. Hence the highest efficiency may be attained in signaling over polystation-lines as well as over single-station lines.

Briefly stated, my invention comprises a system in which a suitable source of ringing-current may be manually connected to a wanted line and will be maintained so connected until the wanted subscriber answers, when it will be automatically disconnected by means of a responsive device having no self-inductance, but quick and positive in its action. Such a responsive device I describe and illustrate herein as a "thermic" controller. This may take the form of a relay, or it may directly control the détent or latch of the switch. In the best embodiment which I have so far devised it comprises a

rocking lever, a triangular strain-plate, and a pair of balanced wires connected from opposite ends of the strain-plate to points on opposite sides of the pivot of the lever. One of these wires is included in the generator-circuit; but the other is insulated therefrom. The size of the wires is such and the parts are so adjusted that sufficient ringing-current may pass to actuate a subscriber's bell without unduly heating the wire and without disturbing the balance established between the two opposite points on the lever. A rise in current in the generator-circuit, however, such as that occasioned by the removal of the subscriber's receiver from its hook and the consequent substitution of his low-resistance talking-set for the high-resistance ringer, will heat the wire on the generator side, so as to expand it, and thereby disturb the balance of the lever and move the same. This lever is used to control the switch.

My invention is illustrated in the accompanying drawings, in which—

Figure 1 is a diagram showing two subscribers' stations and a central station with an operator's cord-circuit thereat and my ringing device applied thereto. Fig. 2 is a similar diagram showing a modified form of ringing device. Fig. 3 is another similar diagram showing a further modification of the ringing device.

Referring to Fig. 1, A and A' are two subscribers' stations fitted with the usual telephones T, ringers Q, and switch-hooks H. The resistance of the ringers is very much higher than that of the telephones. From each station the line-wires 1 and 2 pass to the central office, where they terminate in contacts of spring-jacks J J', normally closed upon terminals connected to line-annunciators L L' and the main battery B. The system shown is provided with a common battery, and it is to be understood that, although this is shown in several units for convenience of illustration they are in reality all one and the same. Since the present invention does not concern itself with line-signals or battery connections or any of the other details of a complete system, I have shown only the essentials, and these in their simplest forms. Thus the line signal-magnets are supposed to control the little targets shown, lifting the same into view when energized and dropping them when deenergized.

For the purpose of interconnecting the lines through the spring-jacks I provide the plugs P P', having tip and sleeve contacts connected, respectively, through the cord-circuit 3 4 5 6. This circuit is conductively divided, but inductively continuous, because of the insertion of a repeating-coil I between the two halves of which the main battery B is included, so as to bridge it across both ends of the cord-circuit. Included in each of the sleeve conductors 4 and 6 is a super-

visory signal-magnet S or S', represented in the same manner as the line signal-magnet L or L'. All of these magnets are supposed to display their signals while current is passing and to retire their signals when the flow of current ceases. The plug P is the answering-plug of the pair, and associated with it is a listening-key, (not shown,) whereby the operator's telephone may be bridged across the cord conductors 3 4 in answering calls. The plug P', on the other hand, is the calling-plug of the pair, and associated with it is a ringing-key K, which, with its associated parts, forms the subject of the present invention. This ringing-key is shown as the plunger k, having a cam-head adapted to be forced by the plunger between the pair of springs k' k², which normally rest in contact with companion springs k³ k⁴, but are thereby spread apart, lifting the inner springs k⁵ k⁶. These outer springs constitute the terminals of a circuit 7 8 9, containing the ringing-generator G. The inner springs k³ k⁴ form terminals for the conductors 5 6 of the cord-circuits, and the middle or active springs k' k² are connected, respectively, to the tip and sleeve of the calling-plug P'.

If no means were provided to hold the plunger k with its head between the springs, the latter would force it out as soon as pressure were removed from the plunger-button; but I provide for this purpose a rocking lever k⁷, a detent-lever k⁸, and the thermic controller K', which constitutes the gist of my invention. The rocking lever k⁷ is supposed to be connected to the plunger k, so as to permit travel of the latter in a straight line—as, for example, by means of a pin and slot, as shown. The lever is pivoted in its middle and at its lower end has an inclined cam-face which rides up over a similar face on the end of the lever k⁸ when the plunger k is pushed in.

The thermic controller K' consists, essentially, of the two thin wires 9 10, the strain-plate k⁹, and the detent-lever k⁸. The strain-plate carries pins k¹², k¹³ on its opposite ends and has a spring k¹¹ attached at an intermediate point. This strain-plate may either be of insulating material or of metal, with the pins insulated. The detent-lever k⁸ also carries two insulated pins k¹⁴, k¹⁵ on opposite sides of its pivot k¹⁰. The wires 9 10 are stretched between the pins on the strain-plate and the pins on the lever and are so adjusted that under normal conditions and when in disuse the parts will stand as shown in Fig. 1. The wire 9 forms a part of the generator-circuit 7 8 9 G, as already pointed out; but the wire 10 is completely insulated. Both wires are maintained taut by the constant pull on the spring k¹¹ on the strain-plate k⁹. Changes in external temperature, as of the surrounding atmosphere, on parts

of the apparatus do not affect the adjustment of the thermic controller, for all such changes affect the two wires 9 and 10 equally, and since they are both maintained equally taut the device may be called "self-compensating." Should one wire become hotter than the other, however, this balance would be destroyed and the lever k^8 would be tilted. This is the condition brought about when the 10 called subscriber answers, as I will now point out in my statement of operation.

Assuming that subscriber A desires to talk with subscriber A', he removes his telephone from the hook, the latter rises, the line-circuit is thereby closed, and current from the main battery B traverses the line and its signal-magnet L, energizing this magnet so that its signal is displayed. Upon perceiving the signal the operator inserts the plug P and, 15 coming in with her listening-key, obtains the number of the line with which connection is wanted. She then takes up the plug P', and after testing the jack J' (if she is working on a multiple board) and finding it idle she inserts the plug P' therein and pushes down the 20 key K. The cam-head of the plunger k thereupon passes between the springs k^1 k^2 , spreading them apart, as already described, and the lever k^7 at the same time rocks upon 25 its pivot until its lower end latches behind the detent-hook on the end of the lever k^8 . The spring k^{11} permits sufficient movement of the lever for this latching, but thereafter pulls the lever up firmly, so that the plunger k is maintained in position, and the generator 30 G is left connected with the subscriber's line through the following circuit: G, 11, k^6 , k^2 , sleeve of plug, jack J', line-wire 2, ringer Q, line-wire 1, jack J', tip of plug, k' , k^5 , 7, 9, 8, 35 40 G. Current flowing in this circuit actuates the ringer Q and produces sounding of the subscriber's gongs. In accordance with modern practice in machine-ringing I prefer to include in the circuit 7 8 9 a continuously 45 driven commutator which will alternately make and break the generator-circuit, or at least divert the current from the ringing-keys, giving, say, two seconds on and four seconds off in succession. This condition 50 55 and this ringing will persist until subscriber A' removes his receiver from the hook. The resistance of his ringer Q, taken with the line resistance, is sufficient to prevent the passage of any large quantity of current. Hence the wire 9 of the thermic controller remains cool. When the subscriber takes down his receiver, however, he closes a shunt around his ringer through the telephone set T, which has a relatively low resistance. The result of this 60 is that current immediately rises in the circuit until the wire 9 becomes very much heated. This heat results in immediate expansion of the wire, whereupon the balance, with its twin wire 10, is destroyed, and the lever 65 k^8 is tilted on its pivot k^{10} by virtue of the

constant tension of the spring k^{11} . This tilting throws down the detent end of the lever, releases the lower end of the rocking lever k^7 , and the plunger k is thereupon permitted to be forced outwardly by the springs k^1 k^2 . As 70 these springs come together they leave the generator-terminals k^5 k^6 and again make contact with their companion springs k^3 k^4 , thereupon reestablishing the continuity of the cord-circuit which before was interrupted 75 in order to prevent "ringing back" over the conductors 3 4 to the calling-station A, where the subscriber has had the receiver to his ear while waiting. As soon as the thermic controller has released the key K the 80 wire 9 again cools off and the detent-lever resumes its normal position. The operator is now informed by the display of the targets of both supervisory magnets S S' that the call has been answered and the subscribers 85 are conversing. When they have finished and hung up their telephones, these targets fall back, and thereupon the operator pulls the plugs P P', reconnecting the line-signal magnets L L' and leaving all parts in condition for another call. 90

In Fig. 2 I have shown a modification of the thermic controller in which this does not directly control the detent-lever k^8 , but controls the same through the intermediation of 95 an electromagnet k^{80} , whose circuit 12 13 is completed to the main battery B when the lever k^{800} is tilted. The thermic controller here acts as a relay to control the magnet k^{80} , and the latter controls the lever k^8 , which 100 in turn controls the rocking lever k^7 of the plunger k of the ringing-key K. The wire 9 of the thermic controller or relay is connected, as before, in the circuit of the ringing-generator G, while the wire 10 is insulated. 105 The operation is the same as in Fig. 1.

In Fig. 3 I have shown another modification, wherein the thermic controller works the detent-lever k^8 through the intermediation of air or gas under pressure. Here X is the 110 receiver or gas-tank, charged to a considerable pressure and having a pipe x connecting it with a chamber x' , containing the piston x^2 , connected to one end of the detent-lever k^8 . Inserted in the pipe x is a slide-valve x^3 , having its stem connected to one end of the lever k^{800} of the thermic controller. In its normal position, with the parts as shown in Fig. 3, the exhaust-channel x^4 of this valve is open to the outer air and in communication with the chamber x' , while that portion of the pipe x leading to the tank X is shut off. Assuming the subscribers to be connected as in the operation of Fig. 1 and subscriber A to have answered, the operation of this modified arrangement is as follows: Current from generator G rises in the circuit 7 8 9, heating the wire 9, as before, so that it expands very considerably. This expansion causes the lever k^{800} to tilt on its pivot k^{10} , lifting the slide- 115 120 125 130

- valve x^3 until the through-channel x^5 renders the passage-way continuous from the receiver or tank X to the chamber x' . Pressure being thus applied to the under side of the piston 5 x^2 , the latter is forced up in the chamber, the lever k^8 is tilted, the rocking lever k^7 is released, and the plunger k springs out, cutting off the generator and reestablishing the continuity of the cord-circuit.
- 10 I am aware that many changes may be made in matters of detail, and this invention may be embodied in many different forms, both of circuits and apparatus; but I wish it distinctly understood that all non-essential 15 changes are within the scope and purview of my claims.
- Having thus described my invention, what I claim, and desire to secure by Letters Patent, is—
- 20 1. In a telephone-exchange system a subscriber's station and a central station and a line-circuit interconnecting them, a signal device of high resistance and a telephone of relatively low resistance in parallel paths 25 across the line at the subscriber's station, means to apply signaling-current to the line at the central station for actuating the ringer, means at the substation to close the telephone-circuit in answering a call, and a 30 thermic controller at the central station adapted to be actuated by the resultant rise in current to remove the same from the line, substantially as described.
2. In a telephone-exchange system, a 35 source of ringing-current, a ringing-key, and a thermic controller therefor included in circuit with the source of ringing-current.
3. In a telephone-exchange system, a line, a ringing-key, and a non-inductive control-40 ling device therefor responsive to changes in line-current.
4. In a telephone-exchange system a ringing-key, a non-inductive controller therefor responsive to changes in current, and means 45 controlled by a subscriber to produce a change in the current in answering a call, substantially as described.
5. In a telephone-exchange system a subscriber's line, means for applying ringing-50 current thereto, means at the subscriber's station to produce a change of current in answering a call, a non-inductive means responsive to said change in current for removing the same from the subscriber's line, substan-55 tally as described.
6. In a telephone-exchange system, a line-circuit having a signal device connected thereto, a source of signaling-current, and a non-inductive controller responsive to cur-60 rent in the line for determining the application of the signaling-current thereto.
7. In a telephone-exchange system a subscriber's station and a central station and a line-circuit interconnecting them, a ringer 65 normally connected to the line at the sub-

scriber's station, means at the central station to connect a source of ringing-current to the line, and a non-inductive controller for said means responsive to changes in the ringing-current, together with means controlled by 70 the subscriber in answering the call to produce such a change in the ringing-current as will affect the controller to disconnect the source from the line, substantially as described.

8. In a telephone-exchange system, a signal-circuit, a source of signaling-current, means for connecting said source to the signal-circuit, and a non-inductive controlling device for said means connected thereby to 80 said signal-circuit to be operated by current therein.

9. In a telephone system a ringing device comprising a switch, a detent for the switch, and a non-magnetic controller for the detent, 85 substantially as described.

10. In a telephone system a non-inductive non-magnetic controller for ringing-circuits, comprising a strain-plate, an operating-lever, a pair of balanced wires extending between 90 the strain-plate and operating-lever, and means for connecting one of the wires in the ringing-circuit to be affected by any rise of current therein, substantially as described.

11. In a telephone-exchange system an 95 operator's automatic ringing device, comprising a manually-operable key, a detent therefor, and non-inductive means controlled by the called subscriber to trip said detent and release the key, substantially as de-100 scribed.

12. In a telephone-exchange system an operative ringing device, comprising a manually-operable key, a detent therefor and a non-inductive controller for the detent connected to line through the key and adapted to be affected by current in the ringing-circ-105 uit, substantially as described.

13. In a telephone-exchange system an operator's automatic ringing device, comprising a key, a detent therefor, and a non-magnetic controller for the detent, substan-110 tially as described.

14. In a telephone-exchange system an operator's automatic ringing device comprising a key, a detent therefor, means for tripping said detent, and a non-magnetic controller for said means, substantially as described.

15. In a telephone-exchange system an 115 operator's automatic ringing device, comprising a key or switch, a detent therefor, a magnet controlling the detent, and a non-magnetic, non-inductive controlling device for the magnet, said controlling device connected through the switch to line in the ring-125 ing-circuit, substantially as described.

16. In a telephone signaling system, the combination with a plurality of subscribers' stations and an exchange-station, signal-re-130

ceiving devices at the subscribers' stations, of a generator at the exchange, a ringing-key for closing the circuit of said generator to said signal-receiving devices, and a thermal controller for said key in the generator-circuit.

17. In a telephone-exchange system, a source of ringing-current, a ringing-key, and a balanced thermic controller included in the circuit of said source, said thermic controller being irresponsive to atmospheric changes but operative by changes of current.

18. In a telephone-exchange system, a line, a source of ringing-current, a key-switch and a thermic controller therefor arranged 15 to be irresponsive to atmospheric changes but responsive to current changes in the line.

In testimony whereof I affix my signature in presence of two witnesses.

WILLIAM W. DEAN.
